DETECTORS OF OIL MISTS AND THE LIKE

Anders Mathisen, Alverstoke, England, assignor to Graviner Manufacturing Company Limited, London, England, a British company

Application April 11, 1958, Serial No. 728,009

Claims priority, application Great Britain April 18, 1957

6 Claims. (Cl. 88—14)

This invention relates to detectors of oil mist and the like.

In the specification of U.S. application Serial No. 629,920, filed December 21, 1956, now U.S. Patent No. 2,907,993, we have described a detector of this kind in which gas, which may be carrying such mist, is drawn through a space across which a light beam is projected. Transparent windows are provided on opposite sides of this space and an electric lamp is mounted behind one window and a photo-electric cell behind the other window, the passage of mist through the space serving to reduce the amount of light from said lamp which falls on the photo-electric cell. The consequent change in output of the photo-electric cell is used to operate appropriate indicating or alarm apparatus.

It has been found that under certain conditions, when using a detector having the construction described in the aforesaid specification, abnormal deposits may occur on the transparent windows. These deposits may not only be of oil or other vapour but may also consist of particles of combustion products such as soot or carbon dust. Whilst such deposits do not in any way prevent correct operation of the detector, nevertheless they render cleaning of the windows necessary at more frequent intervals and are therefore to some extent undesirable. It is believed that such deposits may be increased due to the formation of an air vortex below the inlet of the suction fan, this vortex causing the soot or other dust to be projected outwards from the vortex and deposited upon the windows.

In an endeavour to avoid such troubles, the present invention provides a detector of oil mist and the like comprising a chamber having an inlet for gas which may carry such mist, a window in one wall of said chamber, a second window in another wall of said chamber, a duct extending from a position adjacent but spaced from said first window to a position adjacent but spaced from said second window, a cuff surrounding said first window, said cuff extending through an opening in said duct with the periphery of said cuff spaced from said opening, a second cuff surrounding said second window and extending through an opening in said duct with the periphery of said cuff spaced from said opening, and an outlet for gas from a position in said duct intermediate its two openings, the arrangement being such that gas entering said inlet passes around the outside of either cuff and thence into said duct and out through said outlet.

The invention further provides a detector of oil mist and the like comprising a chamber having an inlet for gas which may carry such mist, a window in one wall of said chamber, a second window in another wall of said chamber, a cuff surrounding said first window and projecting into said chamber, a second cuff surrounding said second window and projecting into said chamber, a duct located in said chamber, said duct having an opening therein into which said first cuff extends, the area of said opening being greater than the cross-sectional area of said

2

first cuff, said duct having a second opening therein into which said second cuff extends, the area of said second opening being greater than the cross-sectional area of said second cuff, an outlet for gas located in said duct at a position between the two openings, and means for mounting a light source behind one window for projecting light through said duct onto a photo-electric cell mounted behind the other window, the arrangement being such that gas passing from said inlet to said outlet passes through the spaces between the cuffs and the respective openings in said duct.

Two constructions of oil mist detectors in accordance with the present invention will now be described, by way of example only, reference being made to the accompanying drawings in which:

Figure 1 is a side view, partly in section, of the first construction of oil mist detector,

Figure 2 is an end view, partly in section of the detector shown in Figure 1, and

Figure 3 is a side view of the second construction of oil mist detector.

Referring firstly to Figures 1 and 2, it will be seen that this construction of detector is generally similar to that shown in Figures 1 to 3 of the drawings accompanying the aforesaid patent specification. As with the previous construction, there is a monitoring chamber 10 through which gas, which may be carrying oil mist, is drawn by means of a suction fan 11 through a suction pipe 12 the inlet 12a of which is connected to the source which is to be monitored. Windows 13 and 14 are provided on opposite sides of the monitoring chamber 10 and an electric lamp 15 is mounted behind the window 14 to project light across the chamber 10 through the window 13 onto a photo-electric cell 16 of the vacuum tube type which is mounted behind the window 13. To compensate for temperature and voltage changes, the output of the cell 16 is balanced by a similar photo-electric cell 17 which has light directed upon it from a light source 18. The light source 18 is mounted on a movable framework 19 which can be moved by rotation of a knob 20 to vary the distance of the light source 18 from the photo-electric cell 17.

In order to reduce dust formation of the kind referred to above, circular cuffs 21, 22 are provided around the windows 13 and 14, the cuffs 21, 22 extending inwardly into the monitoring chamber 10. In the interior of the chamber 10 a rectangular cross-section duct 23 is fitted which overlaps the end of each of the cuffs 21, 22 but does not extend to the walls of the monitoring chamber 10. Within the duct 23 and overlapping the upper side of each of the cuffs 21, 22 an arcuate vortex shield 24 is provided, this shield 24 being secured along its centre line to each of the cuffs 21, 22 and having a larger radius of curvature than the radius of the cuffs 21, 22. An outlet tube 25 extends from an opening in the top of the duct 23 to the inlet of the fan 11.

To give access to the windows 13, 14, a door 23a is provided in the side of the duct 23 and, if desired, a window (not shown) can also be provided in the side of the duct 23 to allow observation through a corresponding window 26a provided in a removable closure plate 26 which is removed to give access to the door 23a.

In operation the gases or vapours from the inlet elbow pipe 12 pass into the duct 23 through its open ends around the sides of the cuffs 21, 22 and this results in a horizontal gas or vapour column in front of the windows 13, 14 which can result in an improved sensitivity to obscuration of the light column. The gases and vapours leave the duct 23 by passing around the edges of the vortex shield 24 and into the outlet tube 25 leading to the fan 11. It is found that where there was previously

a tendency to form a vortex within the monitoring chamber 10, any vortex will now be formed in the tube 25 above the vortex shield 24. It has also been found that with such an arrangement the tendency for solids to be deposited on the windows 13 and 14 is substantially reduced, such deposits occurring either before the gases or vapours enter the duct 23 or after they have passed into the tube 25.

Referring now to Figure 3, the second construction of oil mist detector is arranged to draw gas from the space to be monitored, for example, the crankcase of an engine, via the inlet 30 by having the outlet 31 connected to a suction source; in the case of an engine the latter may be the induction system, in which case no suction fan is required. It will be seen that the inlet 30 opens into a cylindrical monitoring chamber 32 in which a cylindrical duct 33, of smaller diameter than the chamber 32 and of shorter length, is mounted coaxially relative to the chamber 32. At each end of the monitoring chamber 32, windows 34 and 35 are provided, and as with the first construction a lamp 36 is mounted in a housing 37 behind the window 34 and a photo-electric cell 38 is mounted behind the window 35. In this particular construction the cell 38 is a barrier layer cell, for example of selenium, which is embedded in a hermetically-sealing material. A circular cuff 39 is mounted against the window 34 with its end projecting into the flared mouth 33a of the duct 33 and a similar cuff 40 is mounted against the window 35 with its free end projecting into the flared mouth 33b of the duct 33. The outlet pipe 31 opens into the upper surface of the duct 33 at a position midway along its length. Thus, as with the first described construction, gas is drawn in through the inlet 30 and passes towards each end of the chamber 32 through the annular space between the chamber 32 and the duct 33, thence around the ends 33a and 33b respectively and through the annular spaces between the cuff 39 and mouth 33a on the one hand, and the cuff 40 and the mouth 33b on the other hand, and back towards the middle of the duct 33 and out through the outlet 31. In this way, it is ensured that the flow of mist-laden gas is always away from the windows 34 and 35 and danger of deposit of oil and dirt on these windows is considerably reduced. As with the first described construction, the output of the cell 35 may normally be balanced by the output from a similar cell which is located so that its illumination is not affected by the presence of oil mist.

I claim:

1. In a detector of oil mist and the like, a chamber having an inlet for gas which may carry such mist, a window in one wall of said chamber, a second window in another wall of said chamber, a duct extending from a position adjacent but spaced from said first window to a position adjacent but spaced from said second window, a first cuff surrounding said first window, said duct having an opening therein into which said cuff extends with the periphery of said cuff spaced from said opening, a second cuff surrounding said second window, said duct having a further opening therein into which said second cuff extends with the periphery of said second cuff spaced from said further opening, said duct having an outlet for gas located at a position in said duct inter-

mediate its two openings, a suction fan, said suction fan having a suction inlet, said suction inlet being connected to said duct outlet whereby gas entering the gas inlet of said chamber is drawn around the outside of either 5 cuff and thence into said duct and out through said gas outlet, and a deflector plate, said deflector plate being mounted in said duct directly below the gas outlet and having a greater surface area than the area of said gas outlet, whereby any vortex produced by said suction fan is located on the side of the deflector plate facing into said gas outlet.

2. A detector according to claim 1, wherein said deflector plate partly overlaps both said first cuff and said second cuff.

3. A detector according to claim 1, wherein said plate is of arcuate cross-section with its convex surface facing away from the gas outlet in said duct.

4. A detector of oil mist and the like comprising a chamber having a plurality of walls, one of said walls 20 having therein an inlet for gas which may carry such mist, a first window, said window being mounted in one of said walls, a second window, said second window being mounted in a different one of said walls from that in which said first window is mounted, a first cuff surrounding 25 said first window and projecting into said chamber, a second cuff surrounding said second window and projecting into said chamber, a duct mounted in said chamber, said duct having an opening therein into which said first cuff extends, the area of said opening being greater than the cross-sectional area of said first cuff, said duct having a second opening therein into which said second cuff extends, the area of said second opening being greater than the cross-sectional area of said second cuff, said duct having an outlet for gas located in the upper 35 surface of said duct at a position between the two openings, means for mounting a photo-electric cell behind one window, means for mounting a light source behind the other window for projecting light through said duct onto said photo-electric cell, a suction fan, said suction fan having a suction inlet, said suction inlet being connected to said duct outlet, and a vortex deflector plate, said deflector plate being mounted in said duct adjacent but spaced from the upper surface thereof, said deflector plate extending across the full extent of said 40 duct outlet whereby any vortex produced by said suction fan is located on the side of the deflector plate facing into said gas outlet.

5. A detector according to claim 4, wherein said deflector plate partly overlaps both said first cuff and said second cuff.

6. A detector according to claim 4, wherein said plate is of arcuate cross-section with its convex surface facing away from the gas outlet in said duct.
